(57) **CLAIM**

The ornamental design for a snuff package, as shown and described.

DESCRIPTION

FIG. 1 is a perspective view of a first embodiment of the snuff package showing my new design;
FIG. 2 is a top plan view thereof;
FIG. 3 is a left side elevational view thereof;
FIG. 4 is a front elevational view thereof;
FIG. 5 is a right side elevational view thereof;
FIG. 6 is a bottom plan view thereof;
FIG. 7 is a rear elevational view thereof;
FIG. 8 is a perspective view of the second embodiment of the snuff package;
FIG. 9 is a top plan view thereof;
FIG. 10 is a left side elevational view thereof;
FIG. 11 is a front elevational view thereof;
FIG. 12 is a right side elevational view thereof;
FIG. 13 is a bottom plan view thereof; and,
FIG. 14 is a rear elevational view thereof.
The broken lines in the drawings are weld marks and form a part of the claimed design.
